(57) **CLAIM**

We claim the ornamental design for a backpack flap with strap, as shown and described.

DESCRIPTION

This non-provisional design application hereby incorporates by reference the entire disclosure of U.S. non-provisional utility application Ser. No. 16/802,912, filed contemporaneously herewith, entitled Backpack that Employs a Strap Fastener to Secure Utensils in Place.

FIG. 1 is a perspective view of the backpack flap with strap showing environmental features that include knives secured in place with pouches and a strap fastener;

FIG. 2 is a front side view thereof;

FIG. 3 is a rear side view thereof;

FIG. 4 is a left side view thereof;

FIG. 5 is a right side view thereof;

FIG. 6 is a top side view thereof;

FIG. 7 is a bottom side view thereof;

FIG. 8 is a perspective view thereof, which shows the strap fastener partially lifted from the base fastener;

FIG. 9 is a perspective view of an exemplary outer backpack which may be used for the backpack flap with strap;

FIG. 10 is a perspective view of the exemplary backpack in a partially opened state; and,

FIG. 11 is a perspective view of the backpack in a fully opened state of which the backpack flap with strap is a part. Broken lines, such as those representing other compartments and the outer backpack as a whole, are environmental only and form no part of the claimed design. The broken lines on the pouches shown in FIGS. 1, 2, 4, 5, 8, and 11 represent stitching and form part of the claimed design.

1 Claim, 9 Drawing Sheets
